GUY WIRE PROTECTOR

Clarence J. Lemont, South Milwaukee, Wis., assignor to Line Material Company, South Milwaukee, Wis., a corporation of Delaware

Application November 9, 1931, Serial No. 573,727

8 Claims. (Cl. 189—31.5)

This invention relates to a guy wire protector.

It is the usual practice to provide guy wire protectors which clamp about the wire, but it has been found that the prior types of guy wire protectors have certain defects, among which may be noted the following:

The protectors usually completely cover the wire so that broken strands, rusting or other evidences of wear beneath the guy wire protector are not visible. In addition to this, the protectors in some forms contact directly with the guy wire and thus accumulate dirt, grit and moisture and promote rusting and deterioration of the guy wire. Further, it is often difficult to attach the guy wire protectors and auxiliary parts are frequently required to properly attach the protectors to the guy wires, both at their upper and lower ends.

This invention is designed to overcome the defects noted above and objects of the invention are to provide a guy wire protector which is so constructed that the guy wire lies in an open groove in the protector so that it is always visible for inspection, and which is also so made that it affords adequate protection not only for the guy wire itself, but also from the guy wire clamp or clamps, loose strands and other protruding connections.

Further objects are to provide a guy wire protector in which the upper end is so made, for example slotted, that it can be hooked over the wire thereby eliminating the necessity of using bolts, and which is provided with spacers integrally or unitarily formed with the protector, thus spacing the guy wire away from the protector to allow the washing out of dirt and grit and preventing the collection of moisture, thereby securing a longer life for the entire structure and also avoiding the necessity of using loose spacing members.

Further objects are to provide a guy wire protector in which a single curved bolt is used to clamp the protector to the wire and in which the construction is such that the bolt may be carried by the protector itself during shipment and may be merely rocked or slid along its curved arc to permit the positioning of the guy wire within the protector and thereafter be slid back into position and the bolt and washer placed thereon, this curved bolt adequately holding the protector in place.

Further objects are to provide a guy wire protector which is formed with a groove in the protector within which the guy wire is positioned and which, due to the structural shape imparted to the protector, vastly increases its mechanical strength and thereby makes it much stronger against impact, and to provide a guy wire protector which is slotted adjacent its lower end so that the plane of the lower end of the protector is above the guy wire while at the same time permitting the positioning of the protector in place upon the guy wire

without requiring threading of the guy wire through the protector.

An embodiment of the invention is shown in the accompanying drawing, in which:

Figure 1 is a side elevation of a portion of a guy wire with the protector in place. 5

Figure 2 is an enlarged face view of the protector drawn to a larger scale than that shown in Figure 1, such view being greatly shortened.

Figure 3 is an enlarged bottom end view of the 10 protector, the guy wire being shown in section.

Figure 4 is an enlarged sectional view on the line 4—4 of Figure 2.

Figure 5 is an enlarged sectional view on the 15 line 5—5 of Figure 2.

Figure 6 is an enlarged longitudinal sectional view, partly broken away and taken on the line 6—6 of Figure 2.

Referring to the drawing, it will be seen that the guy wire 1 bodily carries the protector, which 20 is indicated generally by the reference character 2. The guy wire protector is stamped from sheet metal, such, for instance, as galvanized sheet steel, or other suitable material. It is an elongated structure provided with a depressed centrally located groove 3 within which the guy wire 25 lies. The general shape of the guy wire protector, as may be seen from Figures 3, 4 and 5, is roughly semi-circular thereby securing considerable mechanical strength. Additional 30 mechanical strength is secured by forming the longitudinally extending groove 3 pressed therein and thus affording a multiple channel effect. This has been found to greatly increase the strength of the protector. 35

It is desirable that the guy wire be spaced slightly from the protector so as to secure the free washing away of any dirt, grit or other material, and also to prevent the collection of moisture. This spacing of the guy wire from the 40 protector is secured by forming spacers 4 from the metal itself, as shown in Figures 2 and 4. These spacers are struck up from the body of the metal, as shown most clearly for instance in Figure 4, and extend transversely across the groove 3. 45 The spacers 4 are themselves provided with small centrally located grooves formed by their centrally depressed portions 4', see Figure 4, within which the guy wire 1 is received.

A curved U-bolt 5 extends through the walls of the channel 3, see Figures 2 and 5, and is provided with a head 6 on one end and a removable nut 7 and washer on the other end. This U-bolt is located intermediate the ends of the protector and securely holds the guy wire to the protector. 55

The upper end of the protector is provided with a transverse slot 8 and with an overhanging upper lip 9 which extends over the upper portion of the guy wire, as shown in Figures 2 and 6. This lip is provided with a downwardly opening groove 60

within which the guy wire is securely seated. The provision of this upper lip eliminates the necessity of providing removable fasteners for the upper end of the guy wire protector.

5 It is to be noted from Figure 2 that the bolt 5 is located between two relatively closely adjacent spacers 4. From Figure 6 it is clear that this construction causes a slight bend in the guy wire and thereby anchors the guy wire protector against longitudinal shifting with reference to the guy wire in an even more efficacious manner than if the bolt merely clamped the guy wire directly and flatly against one of the spacers.

From Figure 2 it will be seen that the grooves 3 15 extend throughout the major portion of the guy wire protector. The lowermost portion 2' is devoid of a groove and is split, as indicated at 10, so that the protector may be slightly sprung and slipped over the guy wire at this portion. This 20 lower portion 2' forms, in effect, an apron which completely covers the guy wire clamp 11 or clamps and also the loose end and loose strands or other protruding connections.

The lowermost portion of this bottom apron 2' 25 is held together by means of a transverse rounded strap or other securing means 12 which may be riveted at one end, as indicated at 13, to one of the portions and may be removably secured by means of a bolt 14 at its other end.

30 It will be seen that a guy wire protector has been formed which is of novel construction, which eliminates a large number of loose pieces which are frequently lost or misplaced in other types of guy wire protectors, and which is inherently 35 structurally strong, thereby resisting impacts to a remarkable degree.

It will be seen further that the guy wire protector is so made that the collection of dirt, grit and moisture is eliminated, and that this result 40 is obtained due to the very construction which enhances the strength and simplifies the formation of the guy wire protector itself.

It will be seen also that the upper tongue eliminates the use of auxiliary clamps or fastening 45 means and that the lower apron affords adequate protection against the guy clamps, loose strands, ends or other projecting portions, thereby in reality affording the maximum protection.

Further, it has been found that the guy wire 50 protector is very easy to make and may be cheaply produced although it has the above enumerated desirable characteristics.

Although this invention has been described in considerable detail, it is to be understood that 55 such description is intended as illustrative rather than limiting, as the invention may be variously embodied and is to be interpreted as claimed.

I claim:

1. A guy wire protector comprising an elongated 60 channel-shaped sheet metal member having a downwardly opening, arched cross sectional contour and having a longitudinally extending groove on its upper side, said protector having a transverse slot adjacent one end thereof forming a lip for hooking over a guy wire, and having 65 means spaced from said slot for retaining the guy wire within said groove, said protector having a lower portion adapted to cover the guy wire.

2. A guy wire protector comprising an elongated 70 sheet metal body portion having a downwardly pressed groove formed therein and extending longitudinally throughout its major portion, said protector having upwardly pressed integral spacers for contact with a guy wire, and means 75 for holding said protector to the guy wire, two

of said spacers being adjacent each other, and a bolt having a curved portion for gripping the guy wire, said curved portion being located between said two spacers.

3. A guy wire protector comprising an elongated 5 channel-shaped sheet metal member having a longitudinally extending, substantially centrally located groove within which a guy wire is adapted to be positioned, said groove being independent of the channel of said protector, said groove being 10 interrupted at spaced intervals by upwardly pressed spacers, and means for holding said protector to the guy wire with the guy wire contacting with said spacers.

4. A guy wire protector comprising a channel-shaped 15 sheet metal member having a longitudinally extending groove for the reception of a guy wire, and having an outwardly pressed, integrally formed spacer for contact with the guy wire, the channel of said protector opening in the opposite 20 direction from said groove, means for holding the guy wire against said spacer, said protector having a transversely extending slot adapted to receive the guy wire and forming a lip to hook over the guy wire. 25

5. A guy wire protector comprising an elongated 30 sheet metal member having an upper and lower portion arranged to pass over a guy wire and having its intermediate main portion arranged to pass under the guy wire, and clamping 35 means intermediate the ends of said protector for clamping the guy wire tightly against said protector adjacent that portion of said protector over which the guy wire passes.

6. A guy wire protector comprising an elongated 35 channel-shaped body portion having a traversely slotted upper end adapted to hook over a guy wire, and having a slotted lower end adapted for positioning over the guy wire, said slots permitting the passage of the guy wire 40 therethrough during the positioning of said protector upon the guy wire.

7. A guy wire protector comprising an elongated 45 sheet metal member having a generally downwardly opening, arch shaped, transverse section, and having an upwardly opening, longitudinally extending groove, said protector having a transverse slot adjacent its upper end forming a lip integral with said protector, said lip being adapted to hook over a guy wire, said 50 groove being adapted for the reception of the guy wire, said protector having its lower portion longitudinally slit to permit the positioning of the guy wire under said lower portion, and means for holding the guy wire within said longitudinally 55 extending groove.

8. A guy wire protector comprising an elongated 60 sheet metal member having a generally downwardly opening, arch shaped, transverse section, and having an upwardly opening, longitudinally extending groove, said protector having a transverse slot adjacent its upper end forming a lip integral with said protector, said lip being adapted to hook over a guy wire, said groove being adapted for the reception of the guy wire, 65 said protector having its bottom portion longitudinally slit to permit the positioning of the guy wire under said lower portion, said protector having integrally formed spacers located within said groove and provided with depressed portions for 70 contact with the guy wire, and a U-bolt located between adjacent spacers for locking said protector to the guy wire.
